UNITED STATES PATENT OFFICE.

NICHOLAS S. VEDDER, OF TROY, AND TOBIAS S. HEISTER, OF LANSINGBURG,
ASSIGNORS TO NICHOLAS S. VEDDER, OF TROY, NEW YORK.

DESIGN FOR COOKING-STOVES.

Specification forming part of Design No. 7,999, dated January 12, 1875; application filed December 30, 1874.
[Term of Patent 3½ years.]

To all whom it may concern:

Be it known that we, NICHOLAS S. VEDDER, of the city of Troy, in the county of Rensselaer and State of New York, and TOBIAS S. HEISTER, of the village of Lansingburg, in said county of Rensselaer, New York, have jointly invented and produced a new and original ornamental Design for Cooking-Stoves, of which the following is a specification, reference being had to the accompanying cut, print, or engraving of a cooking-stove having our said new design.

One part of this invention consists of the design for the compound ornament on the panel A, composed of the vase b, having a scroll-base, c, the pendent side vines d d, having the flowers e e and tendrils, with or without the extension f on the forward vine, the central flower-stem g, and the side stems h h, all shaped and arranged together, in depressed form, in the surface of the panel A, so as to present substantially the same appearance as is represented in the aforesaid cut.

Another part consists of the design for the border ornamentation I, composed of the series of oval ornaments j, having raised scalloped edges and ribs radiating from a center, and connected by stems to two opposite angles of, and alternating with, the series of quadrangular scroll-form ornaments k, all shaped and arranged together, as represented in the aforesaid print.

Another part consists of the design for the oven-door, composed of the compound depressed ornament on the inner panel A, the inner border L, formed by the bead m and series of obliquely-set semi-scrolls n, the inclined surfaces O around the said border L, and the outer border ornamentation I, all shaped and arranged together so as to appear substantially as represented in the aforesaid engraving.

Another part consists of the design for the door or panel P at the end of the fire-box, composed of the inner rectangular panel q, having therein the impression ornament r, formed by top and bottom side scrolls and center stems, and surrounded by the inner border s, the in-

clined surfaces O' and the outer border ornamentations I, all shaped, ornamented, and arranged together substantially as shown in the aforesaid print.

Another part consists of the design for the front fire-door, composed of the panel T, having the lower part u concave outward, and illuminating-windows v with angular tops, the series of inclined curved ornamentations w, and the surrounding border ornamentation I, all shaped, formed, and disposed substantially as represented in the aforesaid engraving.

Another part consists of the design for the leg W, composed of the central ornament x, formed by a central flower-stem with upward-inclined and pendent branches proceeding from a vase, y, having scroll base-branches, all depressed in the convex surface z, having the scalloped border a and side scroll moldings i i, all shaped and combined as represented in the aforesaid cut.

What we claim as our joint invention is—

1. The design for the compound ornament in the panel A, composed of the vase b, with scroll-base c, pendent side vines d d, with flowers e e and tendrils, the central flower-stem g, and the side stems h h, all shaped and arranged in depressed form in the plain surface of the panel A, as herein set forth.

2. The design for the border ornamentation I, composed of the series of ornaments j, connected by stems to, and alternating with, the series of quadrangular scroll-ornaments k, all shaped and arranged together, as specified and shown.

3. The design for the oven-door, composed of the compound depressed ornament in the inner panel A, the inner border L, the inclined surface O, and the outer border ornamentation I, all shaped and arranged together as shown and specified.

4. The design for the door or panel P, composed of the inner panel q, having therein the depressed ornament r, the inner panel-border s, the inclined plain surfaces O', and the outer border ornamentation I, all formed, shaped, and disposed together as shown and described.

5. The design for the front fire-door, com-

posed of the panel T, having the lower part *u* concave, and illuminating-windows *v*, with angular tops, the inner border ornamentation *u'*, and the outer surrounding ornamentation I, all shaped, formed, and arranged as specified and shown.

6. The design for the leg W, composed of the central depressed ornament *x y* in the convex surface *z*, scalloped border *a*, and side

scroll moldings *i i*, all shaped and combined as shown and described.

In testimony whereof we hereunto subscribe our names this 24th day of December, 1874.

NICHOLAS S. VEDDER.
TOBIAS S. HEISTER.
